TOY RAILROAD STATION

Robert L. Butzko, Bridgeport, Conn.

Application September 19, 1951, Serial No. 16,686

Term of patent 14 years

(Cl. D34—15)

To all whom it may concern:

Be it known that I, Robert L. Butzko, a citizen of the United States, residing at Bridgeport, in the county of Fairfield and State of Connecticut, have invented a new, original, and ornamental Design for Toy Railroad Station, of which the following is a specification, reference being had to the accompanying drawing, forming part thereof.

In the drawing,

Fig. 1 is a front perspective view of a toy railroad station embodying my new design, the rear being the same as the front, and

Fig. 2 is an end elevational view of the same.

I claim:

The ornamental design for a toy railroad station, substantially as shown and described.

ROBERT L. BUTZKO.
